UNITED STATES PATENT OFFICE

BENJAMIN F. MIESSNER, OF SHORT HILLS, NEW JERSEY, ASSIGNOR TO MIESSNER INVENTIONS INC., OF SHORT HILLS, NEW JERSEY, A CORPORATION OF NEW JERSEY

ELECTROMAGNETIC SOUND REPRODUCER

Application filed March 7, 1929. Serial No. 344,941.

The present invention relates to electromagnetic sound reproducers, and more particularly to those reproducers including provision for maintaining therein an intense magnetic field.

The invention contemplates in particular the so-called electrodynamic type of sound reproducer in which an intense magnetic field is maintained for interaction with a dynamic coil excited with the sound representing currents.

An object of the invention is the provision of an arrangement whereby the field producing coil of such a reproducer can be excited with a uni-directional pulsating current without disturbing effects on the dynamic coil, and in particular excited with incompletely filtered rectified alternating current, as is had in the now usual practice of energizing the three-electrode vacuum tubes of amplifying systems from commercial alternating current sources.

In the usual mode of construction of electrodynamic reproducers as so-called loud speakers for radio broadcast receivers and electrical phonographs the field coil is made of such electrical dimensions that its inductive impedance is of suitable value as to be well adapted to function as the high inductive impedance in a filter system associated with an alternating current rectifier for supplying the plate and grid energy for amplifier tubes. Such use eliminates the usual choke coil, or one coil if two or more are employed, of such filter systems, thereby saving weight, space and cost of material. However, the incompletely filtered current at the point in a filter system where the field coil must be used in order to replace a choke coil makes for a severely fluctuating field for the dynamic coil of the speaker, with the effect that the resulting hum has heretofore proven undesirably intense.

Endeavor has heretofore been made to neutralize the effect of the fluctuating field on the dynamic coil of the speaker with but little success, and one feature of my invention is the provision of means for neutralizing the hum effect to a degree of perfection not heretofore realized.

My invention will be readily understood from the following description in connection with the figures of the accompanying drawings in which like reference characters represent like parts in the several figures.

Fig. 1 shows in a cross sectional view the usual form of construction of so-called dynamic speakers arranged to include features of my present invention.

Fig. 2 diagrammatically illustrates suitable electrical connections for taking advantage of the features of Fig. 1.

Fig. 3 shows a fragment of the device of Fig. 1 sufficient to illustrate a modified form of my invention.

Fig. 4 shows in detail a useful manner of mounting a dynamic coil and attached reproducing element.

Referring to Fig. 1, a magnetic circuit of the usual form of electrodynamic reproducer is shown to include a cylindrical element 1 of cast iron or other magnetic material having a closure at one end by an integral part of the casing, and a closure at the other end comprising a disk 4 of soft iron or other suitable magnetic material secured to the wall of the cylinder 1 by means of a suitable series of screws 9. A central core 2 of soft iron or other suitable magnetic material is bolted to the base of the cylindrical element 1 by a bolt 3 as shown, the core 2 extending through a circular opening in the front disc 4 as shown, the opening in the disc 4 being of slightly larger diameter than the diameter of the core 2 in order to accommodate a coil 6 secured to a cylindrical projection 7 of a conical sound producing element 8.

A coil 5 usually comprising many turns of fine wire, encircles the core 2, and is arranged with input terminals 13 and 14 through which the field producing or energizing current is supplied.

With the arrangement shown, the energizing of the coil 5 with a unidirectional current produces a magnetic flux which in major part takes a path through the core 2, the gap between the end of the core 2 and the surface of the opening in the disc 4, through the body of the disc 4 to the walls of the cylindrical element 1, and thence through the

base of the cylindrical element 1 to the core 2 to complete the magnetic circuit.

The magnetic flux is thus concentrated in the annular gap between the end of the core

5 2 and the opening in the disc 4, the two sides of the gap being marked N and S to indicate magnetic polarities, but these polarities can be reversed from those indicated without altering the mode of operation. The coil

10 6 is so mounted on the cylindrical extension 7' in the gap as to be movable therein, and preferably without interfering contacts with the gap portions, so that when sound representing currents are applied to this coil

15 through the terminals 15 and 16, there is a motion producing reaction set up between the coil and the intense magnetic field of the gap, resulting in sound reproducing motion being imparted to the cone 7 or other associated

20 sound reproducing element. The usual construction of electrodynamic reproducer endeavors to make the air gap as short as the structure of the coil 6 and its mounting on the cylindrical element 7' will permit while

25 leaving sufficient clearance to prevent frictional contacts, this in order that the flux in the gap may be maintained as intense as possible for a given structure of magnetic system and field producing coil.

30 If the coil 5 is energized from a source, such as rectified and filtered alternating current, having a pulsating component, obviously the resulting flux through the gap will be of unidirectional pulsating character, and

35 will react with the coil 6, with or without the signal representing current flow, to produce motion of the cone 7 that will cause a hum characteristic of the pulsations in the field exciting current, an undesirable feature

40 in sound reproducing devices in general, particularly those used for entertainment purposes such as phonographic reproduction or radio broadcast reception.

45 Because of convenience, the distaste of the public for batteries and the characteristics of the electrical energy required, it is almost compulsory to employ energy derived from commercial alternating current sources for energizing the field coil of current designs

50 of electrodynamic reproducers. Further, the high inductance available in the field coil of commercial electrodynamic reproducers makes these coils particularly suitable as the

55 inductive impedance element of the filter systems commonly used in connection with filtering rectified alternating current for energizing the plate and grid electrodes of three-electrode vacuum tube amplifiers used in radio receivers and electrical phonograph reproducers, and such use saves the expense, weight

60 and space of additional coils for filter purposes in addition to avoiding the employment of a separate source of current for energizing the field coil. For these reasons a satisfac-

tory arrangement for preventing the production of hum when energizing the field coil with uni-directional pulsating current is of great importance, and the features of my present invention permit of this hum elimination to most effective degree.

70 It has heretofore been proposed to provide means, commonly known as a "bucking coil", in an effort to neutralize the effect of the fluctuating field on the dynamic or movable coil and I show a coil 13 in Fig. 1 located adjacent the field coil 5 as illustrating the usual practice towards this end. In this practice the coil 13 is connected in series with the dynamic coil 6, and of such polarity that the induction by the fluctuating field opposes the induction by the fluctuating field in coil 6, the connection being made through terminals 19 and 20.

75 Experience has shown however that such a bucking coil has given very little improvement in the matter of hum production, it being usual to find the hum when the coil is used about $\frac{1}{3}$ of the intensity of the hum without the coil, but still sufficiently intense to be unsatisfactory in the usual entertainment providing apparatus.

80 On mere casual consideration it would seem reasonable to assume that a bucking coil 13 could be so proportioned, or have its output 85 so controlled, as to make it possible to arrive at a proper degree of neutralizing effect to satisfactorily oppose the hum producing effect in the dynamic coil 6, but the fact is that no manner of skilled proportioning of the bucking coil 13, or its output, has heretofore succeeded in arriving at the desired hum elimination results, whereas with the features of my present invention I am enabled to so far reduce the hum that for all practical effect on human audition it may be said 90

95 to be wholly eliminated.

100

105

In arriving at this result, I have found that the practice of locating the bucking coil with respect to the magnetic system in the usual way as shown by the coil 13 in Fig. 1 apparently permits of some induction in the coil by components of magnetic flux not linking with the dynamic coil 6, probably resulting in a disturbance of the induction in the bucking coil to give a different wave

110 form therein from that in the dynamic coil, so that the mere poling of the coil 13 to be generally opposed to the coil 6 does not satisfy all of the requirements for complete neutralization.

115 As a result of this appreciation of a difference in the induction effects I have sought and found a location of the bucking coil with respect to the dynamic coil and its relation to the magnetic flux of the system that marked improvement results, and have further found that by including a shielding effect in a way to govern the magnetic induction in the bucking coil, I can control the

120 production of a bucking induction in such a way as to bring about most complete neu- 125

130

tralization. In Fig. 1, I show my location of a bucking coil 8, of so-called "pancake" form, in very close relation to the gap in which the dynamic coil 6 is located, the bucking coil being shown to encircle the opening in the disc 4, on its inner side, and as close to the disc surface as practical considerations permit. With this location I found in experimenting with a commercial form of 10 reproducer that the hum could be reduced to the order of $\frac{1}{2}$ of that had without the use of a bucking coil, as compared with the reduction to $\frac{1}{3}$ for the location previously discussed. I further find that by covering 15 the coil 8 with a shield of magnetic material 10, magnetically secured to the disc 4 by the screws 12 for instance, that I was enabled to reduce the hum to the order of 1/500th of that had without any hum bucking coil, 20 and compared with the $\frac{1}{3}$ had with coil 13 and the $\frac{1}{2}$ had with the coil 8 without the shielding, so much so that the hum is almost 25 humanly inaudible and the electrical energy of it almost impossible to measure with available measuring apparatus.

Heretofore it has been usual to employ a disc somewhat of the structure of that of the disc 10 secured to the inner side of the disc 4, having a central hole therethrough of 20 substantially the same diameter as the diameter of the core 2 in order to provide means for accurately centering the core 2 in the opening of the disc 4 to provide a gap of 25 permanent dimensions for the dynamic coil 6. In order to prevent this supporting and aligning disc from short-circuiting the magnetic flux from the coil 6, it has been usual 30 to make this disc of non-magnetic material such as brass. In order to use the disc as an effective magnetic shield for my bucking coil 8, I have made the outer portion of it of 35 preferably the best grade of magnetic material, such as pure soft iron, but in order to still utilize the useful function of the disc 45 centering the core 2, I have made the portion of the opening therein which makes contact with the core 2 of non-magnetic material, as brass, having found that a suitable 50 radial depth of non-magnetic material can be satisfactorily pressed into a larger opening of the magnetic portion of the disc. As 55 an example I employ a depth of non-magnetic material of $\frac{1}{8}$ inch, having found that with the external diameter of the non-magnetic portion of the disc substantially equal to, and preferably less than, the internal diameter of the bucking coil 8 entirely satisfactory results are had.

While I have referred to the shield 10 as 60 magnetically secured to the disc 4, this is merely a preferred arrangement. The shield 10 can be moved anywhere along the core 2 between the coil 5 and disc 4, and the coil 8 moved to follow, and still obtain the beneficial 65 results of my invention, though not to the

same degree. Also a construction in which the distance between field coil 5 and bucking coil 8 is increased, as by deepening the cylindrical magnetic element will result in obtaining the beneficial effects of my invention. 70

I have further found that with a given structure the effectiveness of hum neutralization can be affected by some suitable means for variably extending or lessening the effective magnetic projection of the core 2 in order 75 to modify the magnetic field components, as by a screw 12 of magnetic material operating in a threaded hole 12' in the end of core 2. For example, having a coil 8 and shield 10 that does not completely neutralize for coil 6, 80 improvement can be had by screwing element 12 in or out as found by trial to obtain a further reduction in hum. The effectiveness of a given coil 8 and shield 10 also depends upon the axial position of coil 6 with respect 85 to the gap, so that a screw device 12 may prove of value as a final adjustment in quantity production of reproducers to adjust for production differences in positioning coil 6. 90

An adjusting device, such as the screw 12, 95 may be used to advantage in other ways. In those uses of the reproducer with a vacuum tube amplifier system energized from the same source as the coil 5, it may be found uneconomical to try to eliminate all of the hum current arising from such energizing, so that there is some residual hum current accompanying the sound representing currents introduced from the output of the amplifier into coil 6, which may be neutralized by the 100 adjustment of coil 8.

In Fig. 2 the connections for the coils are shown, the arrangement including another way of controlling the neutralizing as between the dynamic coil and the bucking coil. 105 The core 2 of Fig. 1 is again shown with field coil 5 connected to be energized by way of terminals 13 and 14, as from a source 26 of periodically fluctuating unidirectional current. Dynamic coil 6 is shown connected to be 110 supplied with sound representing currents through a transformer 23 connected to, for example, the output terminals 21 and 22 of an amplifier system. The coil 6 is connected in series with coil 8 through a potentiometer 115 24 across the terminals 17 and 18, or other suitable means, permitting adjusting the magnitudes of the hum bucking current collected in coil 8 applied to coil 6, a control equivalent to that provided by the screw 12 120 in Figs. 1 and 2, or which may be used in conjunction with an adjustment had by use of screw 12.

As a practical procedure the coil 8 may be 125 constructed with more turns than needed for neutralizing for a normal position of coil 6, and the potentiometer used for securing an adjustment for taking care of production discrepancies in location of coil 6. Or the potentiometer adjustment may be utilized for cor- 130

recting for residual hum current coming from a preceding amplifier.

In the fragmentary Fig. 3 I show another manner of locating the bucking coil 8 with respect to dynamic coil 6. In this arrangement the core 2 is stopped short of the opening in disc 4 so that a screw attachment 12, with enlarged head as shown, may form the annular gap with the opening in disc 4, with coil 6 located in this gap as before. The screw attachment 12 has its shank threaded for adjustably screwing into a threaded hole 12' in core 2. The coil 8 is inset under an overhang 25 at the rear of the head of screw attachment 12 as shown. This arrangement therefore provides for locating the bucking coil with respect to the dynamic coil so as to have them acted upon by substantially the same flux components of the magnetic system, with an adjustment through screw attachment 12 for finding a final best location of the bucking coil.

While I have found the arrangement of Fig. 3 most effective, yet my investigations have demonstrated that the arrangement of Fig. 1 including the shield 10 can be constructed and arranged to give the better results.

In Fig. 4, a fragmentary illustration, I show an arrangement providing for mechanically positioning the dynamic coil 6 in the air gap longitudinally as well as laterally. In some dynamic speaker construction provision is made for positioning the coil 6 laterally in the gap by inserting a flexible diaphragm 27 at the truncated portion of the conical element 7, which diaphragm has a central hole which permits of securing the center of the diaphragm to a fixed point in the end of core 2, as by a bolt or screw, thus assuring the cylindrical coil support 7' always taking correct position in the gap with respect to core 2. The flexible construction of the diaphragm 27 is relied upon to permit coil 6 to move cone 7 in spite of the central pinning of the diaphragm.

As an additional feature I employ a washer 28 or other suitable arrangement of material, such as rubber or cork, between the core 2 and diaphragm 29, and which can thus be compressed within limits by bolt 29 to permit of longitudinally setting the position of coil 6 in the gap for final hum elimination adjustment in quantity production; and like conditions making such adjustment desirable.

While I do not wish to be understood as offering any specific theory in support of the extraordinary results in hum elimination obtained by me from relocating the bucking coil and shielding it, yet it is thought that a fuller understanding of the principles involved will be had by those skilled in the art by reference to practical observations made by me.

In one investigation the commercial dynamic reproducer I employed had a dynamic coil 6 consisting of 100 turns and a bucking coil 13 located close to field coil 5 as shown in Fig. 1 and having 35 turns, which number of turns I found by investigation to give the minimum hum, though still strong and about one-third of the hum had without the use of any coil. Upon moving the bucking coil to the position at the back of disc 4 I found that I had to increase the number of turns to secure the minimum hum, but reduced the hum to about one-twelfth of that had without any coil. Then with the shield 10 covering a bucking coil of 50 turns I secured a reduction of the hum to about the 1/500th part of the hum without any coil, and substantially down to the limit of human audition.

The feature of having to increase the number of turns to secure minimum hum as the bucking coil was moved away from the field coil clearly indicates that the flux linkage was reduced by the stray field component existing along that part of the core 2 between the field coil and the gap,—that is, that portion of the total flux of the system not passing through the dynamic coil 6,—and since the elimination of linkage of the bucking coil with this stray field improved the neutralizing had it appears reasonable that the poor neutralizing had with the bucking coil located close to the field coil and within the stray field is in some way associated with the stray field component of the total flux which stray field, because of encountering a different magnetic reluctance, differs in phase from the field passing through the dynamic coil 6.

Poor neutralizing can well be accounted for by a distortion difference between the induction in the bucking coil and the dynamic coil making exact opposing impossible, so that amplitude adjustment is not altogether effective.

It seems sound to reason that the stray field component, due to different reluctance by reason of a longer air gap, is out of time harmony or phase with the main field component continuing in the iron path of core 2 to and through the principal but short gap, so that the bucking coil having an induction represented by the vector sum of both components is not in continuous opposed step to the induction in the dynamic coil of the main field component only.

The additional and marked effectiveness of the shield 10 lends weight to suspecting the trouble to rest with the different conduct of the stray field component. It is seen that without the shield it is still possible for strong stray field from core 2 to the rear of the disc 4 to link with the coil 8 without linking the dynamic coil, but which field is largely short circuited from coil 8 when the shield disc is in place.

In other words the fundamental requirement of really effective hum bucking is to have the bucking coil linked only by flux undergoing the same hysteretic influences as the flux linking the dynamic coil. Because of the relation of the 100 turns in the dynamic coil to the 50 turns in the bucking coil I have used, it is apparent that magnitude or volt turns offer no difficulty, being susceptible to the usual principles, as long as like flux characteristics, vectorially speaking, are had for both coils.

Theoretically, therefore, a perfect hum bucking condition would be obtained if the two coils could be made equal and magnetically coincident, but in view of the fact that both coils carry the sound representing currents any approach to this theoretically perfect association for hum bucking must be avoided in order to avoid substantial sound current neutralization. By separating the coils as shown in Figs. 1 and 3 the mutual electrical coupling with respect to sound currents is reasonably small and of no practical consequence.

It is obvious that the passage of sound current through the bucking coil amounts to a loss in efficiency in proportion to the relative electrical and motional impedance of the bucking coil and electrical impedance of the dynamic coil, so that my ability to secure complete neutralization of hum with a bucking coil having but one-half the turns of the dynamic coil is of substantial value in maintaining efficiency.

While I have disclosed my invention with particularity with respect to specific embodiments thereof, no limitations by reason of such choice for explanatory purposes are intended, the invention being one of broad scope capable of numerous adaptations readily apparent to those skilled in the art.

Having fully described my invention, I claim:

- 45 1. In an electromagnetic sound reproducer the combination of a magnet energized by direct current, an air gap in the magnetic circuit of said magnet, a dynamic coil adapted to be energized with sound representing currents operatively located in said air gap, and means for eliminating disturbances in said dynamic coil due to periodic fluctuations of said direct current comprising a second coil connected in opposing series with said dynamic coil, said second coil being so closely associated with said air gap that it is substantially independent of the magnetic leakage of said system not effective on said dynamic coil.
- 50 2. In an electromagnetic sound reproducer the combination of a magnet energized by direct current, an air gap in the magnetic circuit of said magnet, a dynamic coil adapted to be energized with sound representing current operatively located in said air gap, and
- 55 3. In an electromagnetic sound reproducer the combination of a magnet including means for eliminating disturbances in said dynamic coil due to periodic pulsations of said direct current comprising a second coil connected in opposing series with said dynamic coil, said second coil being magnetically shielded from at least a portion of the stray fields of said magnetic system extraneous to said gap not effective on said dynamic coil.
- 60 4. In an electromagnetic sound reproducer the combination of a magnet including means for the energizing thereof by direct current, an air gap in the magnetic circuit of said magnet, a dynamic coil adapted to be energized with sound representing current operatively located in said air gap, a second coil associated with said magnetic system connected in opposing series with said dynamic coil, and a magnetic shield substantially isolating said second coil from stray fields of said magnetic system extraneous to said gap not effective on said dynamic coil.
- 65 5. In an electrodynamic sound reproducer the combination of a magnet including means for the energizing thereof by direct current having an alternating component, an airgap in the magnetic circuit of said magnet, a dynamic coil adapted to be energized with sound representing current operatively located in said air gap, a second coil associated with said magnetic system in close relation to said air gap, said coil being connected in opposing series with said dynamic coil, and magnetically effective means for altering the stray field conditions with respect to one or both of said coils in the neighborhood of said gap so as to produce in said two coils harmonious flux interlinkages as induced from said alternating component of the field.
- 70 6. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 75 7. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 80 8. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 85 9. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 90 10. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 95 11. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 100 12. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 105 13. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 110 14. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 115 15. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 120 16. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 125 17. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.
- 130 18. In an electrodynamic sound reproducer the combination of a magnet including means for the energizing thereof by direct current, an annular airgap in the magnetic circuit of said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material magnetically associated with said disc covering said second coil and through which said core extends in projecting into said circular opening, the opening in said shield through which said core extends being lined with non-magnetic material, whereby said shield serves the additional function of fixedly positioning said core in the circular opening of said disc without unduly short-circuiting magnetic flux from said annular airgap.

said magnet formed by a circular magnetic core projecting into a circular opening in a magnetic disc, a dynamic coil operatively positioned in said airgap, a second coil encircling said circular opening on one side of said disc, said second coil being connected in opposing series with said dynamic coil, and a shield of magnetic material substantially covering said coil having an opening through which said core extends in projecting through said circular opening without said core making magnetic contact therewith.

7. In an electrodynamic sound reproducer the combination of a magnet including a disc of magnetic material having a circular opening therein, a circular core projecting through said opening of such diameter as to form an annular airgap with said disc, a direct current coil on said core for the energizing of said magnet, a dynamic coil operatively positioned in said airgap, and means for eliminating disturbances in said dynamic coil due to periodic fluctuations of said direct current comprising a second coil encircling said core between said direct current coil and said airgap, said second coil being connected in opposing series with said dynamic coil, and a shield of magnetic material interposed between said second coil and said direct current coil.

8. In an electromagnetic sound reproducer the combination of a magnet energized by direct current, an airgap in the magnetic circuit of said magnet, a dynamic coil adapted to be energized with sound representing current operatively positioned in said airgap, and means for eliminating disturbances in said dynamic coil due to periodic fluctuations of said direct current comprising a second coil of less turns than said dynamic coil connected in opposing series therewith, said second coil being associated with said magnetic circuit so as to have a greater flux linkage therefrom than is had by said dynamic coil, and further so associated with said magnetic circuit as to be substantially independent of stray flux extraneous to said airgap not linking said dynamic coil.

In witness whereof, I have hereunto subscribed my name this 5th day of March, 1929.
BENJAMIN F. MIESSNER.

DISCLAIMER

1,830,401.—*Benjamin F. Miessner*, Short Hills, N. J. ELECTROMAGNETIC SOUND REPRODUCER. Patent dated November 3, 1931. Disclaimer filed November 25, 1932, by the assignee, *Miessner Inventions, Inc.*

Hereby enters this disclaimer to that part of the claim in said specification which is in the following words, to wit:

"3. In an electromagnetic sound reproducer the combination of a magnet including means for the energizing thereof by direct current, an air gap in the magnetic circuit of said magnet, a dynamic coil adapted to be energized with sound representing current operatively located in said gap, a second coil associated with said magnetic system connected in opposing series with said dynamic coil, and a magnetic shield substantially isolating said second coil from stray fields of said magnetic system extraneous to said gap not effective on said dynamic coil."
